UNITED STATES PATENT OFFICE.

BERNT GARLLUS, OF MADISON, WISCONSIN.

VAPORIZING DEVICE FOR INTERNAL-COMBUSTION ENGINES.

No. 820,408.

Specification of Letters Patent.

Patented May 15, 1906.

Application filed July 21, 1904. Serial No. 217,674.

To all whom it may concern:

Be it known that I, BERNT GARLLUS, of Madison, in the county of Dane, State of Wisconsin, have invented certain new and useful 5 Improvements in Vaporizing Devices for Internal-Combustion Engines; and I do hereby declare the following to be a full, clear, and exact description of the same, reference being had to the accompanying drawings, forming 10 a part of this specification, and to the letters of reference marked thereon.

This invention relates to devices for commingling hydrocarbon liquid and air to form an explosive mixture for use in internal-combustion engines, the objects of the invention being to provide an inexpensive, compact, and simple device in which the admission of hydrocarbon is controlled by the suction of the engine without requiring the introduction 20 of obstructions in the feed-pipe and whereby with the air may be caused to pass directly over and around the hydrocarbon-inlet and at right angles thereto to effect a more perfect atomizing effect.

25 The invention consists in certain novel details of construction and combinations and arrangements of parts, all as will be now described, and pointed out particularly in the appended claims.

30 Referring to the accompanying drawings, Figure 1 is a vertical section taken longitudinally of the mixer. Fig. 2 is a sectional elevation at right angles to Fig. 1. Fig. 3 is a top plan view.

35 Like letters of reference in the several figures indicate the same parts.

The body portion of the device is in the form of a fitting, which constitutes a part of the intake connections of the engine and at 40 one end is formed for direct connection with the intake-port of the engine or for connection with the pipe leading to said port. The coupling parts or ends may be flanged, as at A, or otherwise formed, as in ordinary pipe 45 connections. The said body is provided with a straight intake-passage B, leading through the same from end to end, and at an intermediate point the gasolene-feed orifice enters the passage from the under side, said 50 gasolene-feed orifice being through a nozzle-like enlargement formed by projections C on the inside and C' on the outside of the fitting. The end of the orifice constitutes a valve-seat for a pointed or needle valve D, 55 extending vertically across the intake-passage and into a chamber E, located above the

passage B. The chamber E communicates with the passage B forward of the gasolene-orifice through a port e, entering the upper part of the chamber E, and above a dia- 60 phragm or disk-piston F, connected with the valve D. Passages G lead from the outside into the chamber beneath the diaphragm or disk F, and consequently the partial vacuum created by the suction of the engine lifts the 65 diaphragm and valve, thereby opening the gasolene-orifice.

A removable cover H is provided for the chamber, and the end of the valve-stem preferably takes a bearing in an opening in the 70 cover to maintain the proper alignment of the valve. To regulate the movement of the valve, an adjustable stop, preferably in the form of a screw I, is located in the cover H in position for the valve-stem to contact therewith, and the stop is provided with a handle or index I', which may register with graduations on the periphery of the cover or chamber to indicate the adjustment, as will be 75 readily understood.

To prevent flooding the engine, the fitting is provided with a dam or wall K forward of the gasolene-orifice, and in some instances a small escape for excess gasolene may be provided, as indicated by dotted lines at L. 80

It will be noted that the projection C', which constitutes the coupling for the gasolene-pipe, is concentric with the chamber E and forms a convenient means for chucking the fitting to finish up the chamber. The 90 whole device is of such form that it may be readily cast. The only machine-work other than the usual coupling connections and drilled ports is in the chamber and its cover, the outside of the latter being preferably ma- 95 chined to present a better appearance.

Owing to the fact that in the preferred construction and as illustrated the diaphragm for controlling the valve is located in a chamber entirely outside of the air-passage, the 100 latter is not restricted, and at the same time in operation the valve will be opened, admitting an appreciable quantity of air not mixed with gasolene.

Should an obstruction occur in the gaso- 105 leno-nozzle, it may be quickly and easily removed, inasmuch as the nozzle is in alignment with the valve-stem opening, and the cover of the chamber and valve may be easily and quickly removed to give access to the 110 nozzle.

In the broader aspect of the invention I do

not wish to be limited to the location of the diaphragm in a chamber outside of the air-passage, although such location is very desirable and practically efficient.

5 Having thus described my invention, what I claim as new, and desire to secure by Letters Patent, is—

1. In a mixer for internal-combustion engines, the combination with the body having 10 the substantially straight inlet-passage therethrough and the nozzle for the admission of hydrocarbonaceous material, projecting transversely into said passage and having its discharge-opening in the end thereof, of a 15 valve having its end fitting in said discharge-opening, a stem on said valve extending across the inlet-opening, a diaphragm connected centrally, directly to said stem and operated by the inspiration of the engine to 20 lift the valve and open the nozzle and means for regulating the inflow of carbonaceous material; substantially as described.
2. In a mixer for internal-combustion engines, the combination with the body having 25 a substantially straight passage therethrough, a nozzle for the admission of hydrocarbonaceous material projecting transversely into said passage; and a valve for said nozzle, of a diaphragm controlling said valve, a chamber 30 at one side of the said passage through the body and in which said diaphragm is mounted, the chamber being open to the atmosphere on one side of the diaphragm and open to the passage in the mixer on the other side 35 of the diaphragm; substantially as described.
3. In a mixer for internal-combustion engines, the combination with the body having the substantially straight inlet-passage therethrough and the nozzle for the admission 40 of hydrocarbonaceous material projecting transversely into said passage and a valve for closing said nozzle having a stem extending through the wall of the passage opposite the nozzle, of a chamber outside of the passage, 45 a diaphragm in said chamber extending in a plane at right angles to and directly connected centrally to the valve-stem, and a port leading from the chamber above the diaphragm communicating with the passage forward of 50 the nozzle; substantially as described.
4. In a mixer for internal-combustion en-

gines the combination with the body having the intake-passage therethrough, the nozzle for the admission of hydrocarbonaceous material projecting transversely into said passage from the under side and the chamber formed in an enlargement on the body opposite said nozzle and above the passage, of a valve for the nozzle having its stem extending across the passage and into the chamber, 55 a diaphragm on said valve-stem within the chamber, an adjustable stop for limiting the upward movement of the valve and a port in said chamber above the diaphragm open to the passage; substantially as described. 65

5. In a mixer for internal-combustion engines, the combination with the body having the substantially straight intake-passage therethrough, the nozzle for the admission of hydrocarbonaceous material projecting 70 into said passage from the under side and the chamber formed in an enlargement of the body above the passage, the upper part of the chamber being open to the passage, of a valve for the nozzle having its stem extending across the passage and into the chamber, 75 a diaphragm in the chamber to which the valve-stem is connected a removable cover for the chamber and a stop-screw in the cover for limiting the movement of the valve; sub- 80 stantially as described.

6. In a mixer for internal-combustion engines, the combination with the body having the intake-passage therethrough, the nozzle projecting into said passage from the under 85 side, a chamber formed in an enlargement of the body opposite said nozzle and open near the top to the passage forward of the nozzle and a wall in the bottom of the passage, of a valve for the nozzle having its stem extending across the passage and into the chamber, 90 a diaphragm in the chamber to which the valve is connected, a removable cover for the chamber, a screw in said cover for limiting the opening of the valve and an index connected with said screw for indicating its adjustment; substantially as described. 95
